UNITED STATES PATENT OFFICE.

LOUIS REINHARD, OF MILWAUKEE, WISCONSIN, ASSIGNOR TO THE MECHANICAL APPLIANCE COMPANY, OF MILWAUKEE, WISCONSIN, A CORPORATION OF WISCONSIN.

SWITCH.

1,153,257.

Specification of Letters Patent. Patented Sept. 14, 1915.

Application filed February 28, 1914. Serial No. 821,771.

To all whom it may concern:

Be it known that I, LOUIS REINHARD, a citizen of the United States, residing at Milwaukee, in the county of Milwaukee and 5 State of Wisconsin, have invented new and useful Improvements in Switches, of which the following is a full, clear, concise, and exact description, reference being had to the accompanying drawing, forming a part of 10 this specification.

My invention relates to improvements in switches, and particularly to switches operated by centrifugal force.

One of the objects of my invention is to 15 provide a centrifugally operated switch which shall have a snap movement and one in which the movable members shall move to closed position with a quick snap action thereby preventing arcing at the contact 20 points.

For the purpose of disclosing my invention I have illustrated the same in connection with a switch operated to short-circuit the windings of an alternating current motor 25 after the rotor thereof has reached a predetermined speed.

In the drawing disclosing one embodiment of my invention, Figure 1 is a front elevation of a switch embodying my invention, the cover of the casing inclosing the switch being removed; and Fig. 2 is a sectional view taken on the line 2—2 of Fig. 1.

In the embodiment illustrated I have shown a switch for short-circuiting the windings of the rotor of an alternating current. The switch illustrated comprises a casing 1 which is secured by any suitable means to the shaft 2 of the rotor of the alternating current motor 3. This casing has mounted 30 therein a plurality of switch contacts which comprise spring fingers 4 mounted upon posts 5. These posts are secured in the back of the casing and are insulated from the casing by suitable insulating bushings 6, and 35 the posts, at their rear ends, carry binding screws 7 to which the windings of the rotor may be connected. In the switch illustrated I have shown five of these posts which carry 40 spring fingers. An arm 8 is pivotally 45 mounted upon a stud 9 by means of a screw 10 within the casing and is provided at its outer end with a weight 11. Integrally formed with the arm is an arc shaped member provided with a plurality of radial pro- 50 jections or contacts 12 adapted to make

contact with the spring fingers 4 of the different posts. The arm and arc shaped member form a ring provided with contacts by which the various posts will be short-circuited on one another. The contact members 60 12 are held out of contact position by means of a coiled spring 13 which is mounted upon a post 14. The upper end of this post projects through an opening in the arm 8 and the lower end of the post is provided with 65 a head 15 against which one end of the coiled spring abuts. This head bears upon the end of a pointed screw 16 mounted in the casing, which screw is held in its adjusted position by means of a lock nut 17.

The operation of the device so far described is as follows: When the motor reaches a predetermined speed the centrifugal force induced by the rotation of the switch will cause the arm to move on its pivot against the action of the spring 13 and move the contacts toward a closed position, or to a position to cause the projections 12 to engage the spring fingers 4 on the various posts. I have discovered, however, that this 70 movement is more or less slow, and, as a result, the contacts are burned out due to the arcing between the same when they are moved slowly into engagement with each other. In order to prevent this movement 75 and in order to provide a snap action, I provide a snap spring 18 mounted on a post 19 secured in the casing and provided, at its 80 outer end, with a semi-spherical trigger 20. This trigger is adapted to fit in a rounded 85 recess formed in the arc shaped portion, which recess, however, is of such depth that the ball-shaped trigger will not pass below its center point. This trigger is 90 adapted to engage in its recess when the contacts are in their open position and when the speed of the switch has reached a predetermined point; the centrifugal force causing the arm to tend to rotate in its pivot 95 9 will cause the trigger 20 to ride out of its recess, thereby releasing the contacts and permitting them to quickly snap over to 100 closed position.

It will be noted that due to the construction of this switch no matter in which direction it is rotated the centrifugal force 105 will act equally well to cause it to close.

While I have shown and described one form of my invention it will be understood that changes may be made in the embodiment.

ment thereof without departing from the spirit of the invention as set forth in the appended claims.

Having thus described my invention what 5 I claim as new and desire to secure by Letters Patent is:—

1. In a switch, the combination with a rotatable member, of a plurality of contacts carried thereby, an arm pivotally mounted 10 on said rotatable member and carrying an annular contact carrying member moved by centrifugal force to place the contacts carried thereby into engagement with said relatively stationary contacts, and means for holding said arm against movement until said rotatable member has reached a predetermined speed.
2. In a switch, the combination with a rotatable member, of a plurality of contacts 20 carried thereby and circumferentially spaced, an arm pivotally mounted on said rotatable member and carrying an annular contact carrying member moved by centrifugal force to place the contacts carried thereby into engagement with said relatively stationary contacts, and means for holding said arm against movement until said rotatable member has reached a predetermined speed.
3. In a switch, the combination with a 25 rotatable member, of a plurality of contacts

carried thereby and circumferentially spaced, an arm pivotally mounted on said rotatable member and carrying an annular member having a plurality of radial contact arms, said annular member being moved by centrifugal force to place said radial arms in contact with said relatively stationary contacts, and means for holding said arm against movement until said rotatable member has reached a predetermined speed. 35

4. In a switch, the combination with a rotatable member, of a plurality of contacts carried thereby, an arm pivotally mounted on said rotatable member and carrying an annular contact carrying member moved by 40 centrifugal force to place the contacts carried thereby into engagement with said relatively stationary contacts, and a trigger comprising a semi-cylindrical spring mounted member engaging a semi-cylindrical recess for holding said contact carrying member against movement until the centrifugal force reaches a predetermined point. 45

In witness whereof, I have hereunto subscribed my name in the presence of two 50 witnesses.

LOUIS REINHARD.
